UNITED STATES PATENT OFFICE.

ROBERT RICHARDI, OF RICHMOND, VIRGINIA.

CLOTHES-PIN MACHINERY.

SPECIFICATION forming part of Letters Patent No. 734,957, dated July 28, 1903.

Application filed July 16, 1902. Serial No. 115,878. (No model.)

To all whom it may concern:

Be it known that I, ROBERT RICHARDI, residing at Richmond, in the county of Henrico and State of Virginia, have invented 5 certain new and useful Improvements in Turning-Lathes, of which the following is a specification.

My invention relates to improvements in multiple or many-spindled lathes for turning 10 clothes-pin blanks and other like forms from blocks of wood; and it primarily seeks to provide a simple, cheap, and easily-operated machine whereby the blocks of wood are shaped with the utmost degree of accuracy 15 and the minimum amount of waste.

This invention comprehends a machine of the character stated in which the block to be operated upon is fed by hand or otherwise to a rotatable chuck, which automatically 20 chucks the block and then carries or feeds it to a revolving cutter, where the block is formed into the desired shape, after which the block is automatically released from the chuck.

Reference is had more particularly to the accompanying drawings, in which like numerals of reference indicate like parts in all the figures, and in which—

Figure 1 is a top plan view of my invention. Fig. 2 is a vertical longitudinal section thereof, taken on the line 2 2 of Fig. 1 and looking in the direction of the arrow. Fig. 3 is a cross-sectional view taken practically on the line 3 3 of Fig. 1 and looking in the direction of the arrow. Fig. 4 is a detail diagrammatic view of one part of the chuck mechanism and showing only four spindle-holding members. Fig. 5 is a detail section on the line 5 5 of Fig. 4. Fig. 6 is a similar 40 view on the line 6 6 of Fig. 5. Fig. 7 is an enlarged detail perspective view of one of the block-holding spindle members. Fig. 8 is a longitudinal section thereof, and Figs. 9 and 10 are detail views hereinafter referred to.

1 indicates a suitable base or standard upon which in suitable bearings 2 2 is mounted the main or drive shaft 3, carrying at one end the pulleys 4 4^a, for a purpose presently to appear. Mounted upon the shaft 3 is the 45 cutter-carrying frame 5, which consists of the side members 5^a 5^b, between which in a radial arrangement and upon cross-pieces 5^c

are mounted the cutters 6, as best shown in Figs. 1 and 2. The side members 5^a 5^b are open, as at 5^x, to allow of the easy discharge 55 of the shavings. The cutters 6 have their cutting edges 6^a so constructed to give the desired shape to the block.

Held to rotate in bearings 7 7 on the frame 1 is a second shaft 8, carrying at one end the 60 drive-gear 8^a, with which meshes the worm-gear 8^b, held to rotate in bearings 8^c 8^e and carrying at its lower end the drive-pulley 8^d, as clearly shown in Figs. 1 and 3. The worm-gear derives its motion from the main drive- 65 shaft 3 through the medium of the belt 4^b, taking around the pulleys 4^a and 8^d. (See Fig. 1.)

Upon the shaft 8 is mounted and held to rotate therewith the chucking mechanism, 70 (designated generally by the reference-number 9.) The chucking mechanism 9 consists, essentially, of two circular disks 10 11, suitably placed apart and which carry the chucking-spindles hereinafter referred to. 75

Referring now more particularly to Figs. 4, 5, and 6, it will be seen the disk 10 has a series of radial slots 10^a, (one for each chucking-spindle,) in which is held to slide the spindle-carrying block 10^b. This block 10^b has 80 side flanges 10^c 10^e, forming guideways 10^d, as clearly shown in Figs. 4 and 6. In a bore 10^e is held to rotate a spindle 10^f, having a roller 10^g at its outer end and a spur 10^h at its inner end for a purpose presently readily understood. The spindles 10^f are so constructed as to have no longitudinal motion in the bore 10. Buffer-springs 10^x serve to maintain the blocks 10^b, and therefore the spindles 10^f, to their outermost position. The disk 11, 90 like the disk 10, has a series of radial slots 11^a, equal in number and similarly arranged to those in the disk 10. Held to slide in the slots 11^a of the disk 11 are a series of spindle-carrying blocks 11^b, of a like construction to 95 the blocks 10^b on the disk 10. The blocks 11^b, like the blocks 10^b, have side flanges 11^c 11^e and buffer-springs 11^x.

Referring now more particularly to Figs. 2, 7, and 8, it will be seen the blocks 11^b have 100 suitable bores 11^e, in which are held to rotate the spindle-carrying sleeves 12, carrying a roller or pulley 12^x at their inner ends, as shown. Held for a longitudinal movement

in the bore 12^a in the sleeve 12 is what I term the "chucking-spindle" 13, which carries at its inner end the spur 13^a for engaging the block, the other end 13^b of which engages an aperture 14^a in the lever 14, which lever 14 is pivoted at 14^b to the bracket extension 11^c of the block-flange 11^c, as clearly shown in Figs. 7 and 8.

Held free to move upon rods 15 15^a and 10 made fast to or integral with the inside flange 11^c of the block 11 is a cross-piece 16, connected to the lever 14 by a rod 16^a. (See Figs. 7 and 8.) Upon the extreme outer ends of the rods 15 15^a are circular adjusting-nuts 15^x, 15 between which and the cross-piece 16 are buffer-springs 16^x 16^y for holding the lever 14 and the chucking-spindle 13 in their normal or chucking position. At the free end of the lever 14 is a friction-roller 14^y, for a purpose 20 presently to appear.

17 17^a indicate what I term "guide members." These guide members are fixedly connected to the frame 1 of the machine-bed and have at their upper ends a curved portion 17^x for engaging with the rollers 10^x 12^x, as will be clearly understood by reference to Figs. 2 and 4 of the drawings.

Rigidly connected to the frame 1 of the machine is a cam-guide 20 for withdrawing 30 the chucking-spindles from and releasing the finished block.

At the entrant end of the machine is mounted upon a suitable standard a trough or table 25, having adjustable guides 26 fastened to the under side thereof by means of bolts 26^a in any approved fashion.

From the foregoing, taken in connection with the accompanying drawings, the operation of the invention will best be understood 40 as follows:

Operation: The blocks or stock are fed to the chucking mechanism by pushing them along the table or trough 25 and are held in the proper position by the guides 26, after 45 which they are chucked by reason of the chucking-spindle lever 14 being released from the cam-guide 20, which allows the buffer-springs 16^x to operate to chuck the block. The block is then carried from the upper half 50 of the circle described by the chucking mechanism toward the cutter device. As soon as the rollers 10^x and 12^x come in contact with the curved portion of the guide members 17 17^a the buffer-springs are compressed. This 55 causes the stock to be carried in the arc of the circle described by the cutter-blades during the cutting operation. In other words, the block after being chucked first moves in the arc of the circle described with its center as the chucking-mechanism-carrying shaft 60 and then through the arc of a circle described with the main drive-shaft as a center, it being understood the arc of the circle through which the stock travels when operated upon 65 by the cutter is of sufficient length that the stock will receive at least a full rotation while under influence of the cutter-knives, it being

also understood that the cutter-knives revolve more rapidly than the block-carrying chucking mechanism. The rotation of the 70 block being produced by reason of the rollers 10^x 12^x being in close contact with the curved portion 17^x of the guides 17 17^a. (See Figs. 2 and 4.) After leaving the guides 17 17^a the stock again travels in the arc of its own circle, the buffer-springs 10^x 11^d serving to again move the chucking-spindles to their outermost radial position. Referring now more particularly to Figs. 2 and 3, it will be seen that after the chucking-spindle-carrying 80 blocks leave the influence of the guides 17 17^a the roller on the lever 14 will engage the cam-guide 20 and release the finished block. As soon as the roller reaches the end 20^x of the cam-guide 20 it will "run off" and again 85 chuck another block.

While I have shown circular rollers upon the chucking-spindles, yet I desire it understood that when different shapes are to be worked out of the block other styles of rollers may be used—as, for instance, a hexagonal (see Fig. 10) or octagonal. (See Fig. 9.) Furthermore, I desire it understood that in practice I may find it desirable to mount the spindles upon ball-bearings. Neither do I 95 desire to limit myself to any specific number of chucking-spindles or cutter-knives, since any desired number can be used without departing from the scope of the appended claims.

Having thus described my invention, what I claim, and desire to secure by Letters Patent, is—

1. In a machine as described, a rotatable cutter mechanism adapted to rotate around 105 one axis, a rotary stock-feeding mechanism adapted to rotate around another axis, said feeding mechanism including chucking-spindles for holding the stock, said chucking-spindles being adapted to rotate with the feed 110 mechanism, a guide for engaging said spindles when under the influence of the cutter mechanism, whereby the stock first moves in the arc of a circle having as its center the axis of the feeding mechanism, then, while 115 under the influence of the cutter mechanism, in the arc of a circle with the axis of the cutter mechanism as a center as and for the purposes described.

2. A machine of the class described, comprising a rotatable cutter mechanism, radially-arranged means for feeding the stock to the cutter mechanism in the arc of one circle, means for guiding the stock in the arc of the circle described by the cutter mechanism 125 while the said stock is being operated upon, substantially as shown and for the purposes described.

3. A machine as described, comprising in combination a rotatable cutter mechanism, a 130 radial feeding mechanism for feeding stock to cutter mechanism in the arc of one circle said feeding mechanism including a pair of circular disks, radially slotted and carrying

chucking and releasing mechanism, said mechanism comprising a slidable block 11^b having a bracket portion 11^x and adapted to slide in the radial slots of one of the circular disks, said mechanism further including a spindle-carrying hub 12 and the spindle 13, said spindle 13 being adapted for longitudinal movement within the hub 12, a lever 14 carrying a friction-roller 14^y at one end, said lever 14 being pivotally connected to the bracket portion 11^x, a cam-guide for controlling the movement of said spindle, means for rotating said feeding mechanism and said cutter mechanism, whereby the chucking-spindle 13 will travel first in the arc of the circle described by the feeding mechanism, fixedly-mounted guides for causing the spindle 13 to move in the arc of the circle described by the cutter mechanism when the stock is being operated upon by the cutter mechanism, substantially as and for the purposes described.

4. In a machine of the class described, a chucking mechanism, said chucking mechanism comprising a block 11^b, a rotatable sleeve 12 mounted within the block 11^b said sleeve

being formed with a roller 12^x at one end, a spindle 13 mounted within a bore 12^a in the sleeve 12 and adapted for longitudinal movement therein, a bracket 11^x formed integral in the block 11^b, the lever 14 pivotally connected to the bracket 11^x and carrying a friction-roller 14^y at its free end, said lever being adapted to engage the spindle 13, the buffer-spring 16^x and block 16 loosely mounted upon the spindles 15 15^a, said spindles 15 15^a being fixedly mounted upon the block 11^b, said block 16 and said lever 14 being connected to each other by a rod 16^a, said block and said buffer-spring serving to hold the lever 14 and spindle 13 in their normal or chucking position, all being arranged substantially as shown and for the purposes described.

In testimony whereof I have signed my name to this specification in the presence of two subscribing witnesses.

ROBERT RICHARDI.
